CLAIM

The ornamental design for an earphone case, as shown and described.

DESCRIPTION

FIG. 1 is a front and top perspective view of an earphone case, showing our new design;

FIG. 2 is a rear and bottom perspective thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the earphone case that form no part of the claimed design. The logo shown in FIGS. 1 and 5 forming part of the claimed design is a registered trademark of Shenzhen Dancing Future Technology Ltd.
